CORD ASSEMBLING APPARATUS

Dan O. Hannan and Samuel M. Martin, Baltimore, Md., assignors to Western Electric Company, Incorporated, New York, N. Y., a corporation of New York

Application December 8, 1942, Serial No. 468,232

10 Claims. (Cl. 57—25)

This invention relates to a cord assembling apparatus and more particularly to an apparatus for use in assembling a plug and multi-conductor cord and in applying a twist to the conductors.

It is an object of the present invention to provide a simple and inexpensive apparatus for quickly assembling articles.

In accordance with one embodiment of the invention, apparatus is provided for assembling a multi-conductor cord to a plug, leaving the terminal ends of the cord free of the plug. In this apparatus, a spindle supported chuck is provided with spring clips for engaging and holding a plug in its free end and the head of the chuck has pivoted on it a plurality of conductor terminal engaging clamps resiliently urged to grip the terminals of a plurality of conductors by springs individual to each clamp and nested in a slidable collar normally held against axial movement with respect to the chuck but releasable for axial movement whereby all of the clamping jaws may be simultaneously released from the conductor terminals. The spindle may be rotated to facilitate wrapping and attaching a binding wire around the conductors and plug and for twisting the conductors.

A better understanding of the invention will be had by reference to the following detailed description when considered in conjunction with the accompanying drawing, wherein

Fig. 1 is a side elevational view partly in section of an apparatus embodying the invention showing some of the terminal gripping clamps in elevation;

Fig. 2 is a fragmentary side elevational view of the spindle supported chuck partially in section showing the details of the clamps for holding a plug in the end of the chuck;

Fig. 3 is a vertical sectional view taken substantially along the line 3—3 of Fig. 1 in the direction of the arrows; and

Fig. 4 is a side elevational view of the terminal end of a cord formed in the present apparatus.

Referring to the drawing, wherein like reference characters designate the same parts throughout the several views, it will be seen that the apparatus includes a standard 10 having journalled in it a spindle 11, which is held in place in the standards by a pair of retainer collars 12 and 13. Formed integrally with the collar 13 is a crank 14 having a handle 15 freely rotatable on its outer end whereby rotation may be imparted to the spindle manually, the collars

12 and 13 being fixed to the spindle 11 by means of set screws or pins 16 and 17, respectively. The spindle 11 has, at its left end (Figs. 1 and 2), a cylindrical head or chuck 18 which is tapered at its left end and has a central socket 19 formed in it for receiving the tip end of a plug 20 to which conductors 21—21 are to be attached. The plug 20 is provided with four grooves 22 extending along its outer surface in which the conductors 21 are to be seated in the completed cord. In addition, the plug 20 has a projecting portion 23, which fits into the socket 19 in the end of head portion 18 of the spindle 11. This extending projecting portion 23 of the plug terminates at a shoulder 24, from which the plug tapers down to a place where the bases of the grooves in the plug are approximately the same distance from the axis of the plug as the surfaces of the projecting portion 23. The shoulder 24, when the plug is placed in the spindle head, will engage the end of the head or chuck 18.

By reference to Fig. 2, it will be seen that the plug 20 may be held in the chuck 18 at the end of the spindle by means of spring clamps 25, of which any desire number may be provided, the spring clamps being fixed to the head portion 18 and extending out beyond the end of the head portion to terminate in a rounded projection 26, whereby a plug, in being inserted in the end of the spindle, will engage the rounded portion 26 to flex the springs, which will immediately return to the position shown in Fig. 2 to hold the plug in the chuck 18.

The tapered end of the chuck 18 is provided with a series of four slots 27 in alignment with the four slots 42 in the head of the plug 20. These slots 27 extend from the left end of the chuck 18 at an angle to the axis thereof and terminate in depressions 28. Just to the right (Figs. 1 and 2) of the depressions 28, the chuck 18 has notches 29 cut in it for receiving the pivot arms 30—30 of clamps 31—31. The clamps 31 are pivotally mounted by means of the pivot arms 30 on pins 32 suitably mounted in the head portion 18 and the clamps each have a conductor engaging surface 33 and a terminal engaging pin 34 mounted upon them, the conductor engaging portion being designed to engage the conductors 21 and hold them in the grooves 22 and 27, whereas the pin 34 will extend through an aperture 35 in a terminal 36, one of which is secured to each of the conductor 21.

Pivotally connected to each of the clamps 31 is a link 37, which is, in turn, pivoted on a plunger member 38. The plunger member 38 is slid-

ably mounted within a bore or pocket 39 formed in a collar 40 which surrounds the head portion 18 and is provided with a shoulder 41 adapted to normally engage a shoulder 42 at the juncture of the shank and head portion 18 of the spindle 11. Each of the bores or pockets 39 has a compression spring 43 mounted in it for normally urging the plunger 38 to the left (Figs. 1 and 2), thus to normally urge the clamps 31 into engagement with the conductors 21 and terminals 36. However, the plungers 38 are each provided with a handle 44, whereby they may be moved to the right (Figs. 1 and 2) to disengage their respective clamps from the conductor 21 associated with it.

The collar 40 has a slot 45 formed in it into which extends a pivot portion 46 of a latch 47. The slot 45 is also adapted to receive compression spring 48, which normally urges the latch 47 to rock clockwise (Fig. 2) to a position where its latching portion 49 will engage the collar 12 and will prevent the collar 40 from moving to the right. However, by compressing the spring 48, the latching portion 49 may be cammed up out of engagement with the left face of the retainer collar 12 and the collar 40 may then be moved to the right to simultaneously release all of the clamps 31 from their associated conductors 21 and conductor terminals 36. The plug 20 is provided with a circumferentially extending groove 50 for receiving servings of wire 51 wrapped around the conductors 21 and the plug 20 for attaching the plug 20 and conductors 21 together.

In the operation of the apparatus, the latch 47 may be depressed and the collar 40 moved to the right, thereby to rock all of the clamps 31 away from the left end of the head or chuck 18 and a plug 20 may then be inserted with its projecting portion 23 extending into the central pocket 19 of the chuck, where the plug will be held by the spring 25. As soon as the plug has thus been placed in position, the collar 40 may be pushed to the left to permit the latching portion 49 of latch 47 to move down to position to be engaged by the retainer collar 12. After these operations have been performed, a group of four conductors 21 with their attached terminals 36 may be separately clamped in place in the aligned grooves 22 and 27 in the plug 20 and the head or chuck 18 of the spindle 11 with the surface 33 of the clamp engaging the conductors and the pins 34 extending through the central aperture 35 in the terminals 36. After the plug 20 and conductors 21 have thus been attached to the head portion 18, the spindle 11 may be rotated to apply a serving of wire 51 to the plug and conductors 21, the serving 51 being wound in the circumferential groove 50. After the wire has thus been tightly wound on the assemblage, it may be soldered to hold it in place and further rotation may be imparted to the spindle 11 while holding the opposite end of the conductors 21 to twist the conductors and form them into a cable whereupon the far end of the cable may have a serving of twine or wire wrapped around it to retain it in place, whereby the twist in the wires will be retained therein.

While the apparatus described hereinbefore has been described as one in which four conductors may be attached to a single plug, it will be understood that any desired number of conductors may be attached to a plug or plug member in this manner by providing the necessary number of clamps for engaging the conductors to be attached to the plug.

What is claimed is:

1. In an assembling apparatus, a spindle, a spring chuck on the end of the spindle for receiving a plug, individually releasable clamps surrounding said chuck for gripping conductor terminals, resilient means normally holding said clamps closed, a collar slidably on said chuck for supporting said resilient means, and latching means for normally holding said collar in position to render the resilient means operative.
- 5 2. A cord assembling apparatus comprising a manually rotatable chuck, a recess in the free end of the chuck for receiving a plug, means for retaining the plug in said recess, clamps surrounding said chuck adjacent said recess for engaging conductors, means for normally urging said clamps to engage a conductor, individual means for releasing said clamps, and means common to all of said clamps for releasing them.
- 10 3. A cord assembling fixture comprising a manually rotatable plug holding chuck, clamps mounted on said chuck, a manually operable plunger connected to each clamp, means for urging said plungers to actuate the clamps, and releasable means for normally holding said urging means in operative position.
- 15 4. A cord assembling fixture comprising a manually rotatable plug holding chuck, a plurality of clamps pivotally mounted about the circumference of said chuck for rotation with the chuck, means individual to each clamp for resiliently urging them to operative position, manually operable means for individually releasing said resilient means, and manually operable means common to all of said clamps for releasing them.
- 20 5. A cord assembling fixture comprising a manually rotatable plug holding chuck, a collar rotatable with and slidably longitudinally on said chuck, a plurality of plungers resiliently mounted in said collar, clamping means pivoted externally on said chuck, linkage connecting said clamping means and plungers, and means for normally holding said collar in a predetermined position longitudinally of the chuck.
- 25 6. A cord assembling fixture comprising a manually rotatable plug holding chuck, a collar rotatable with and slidably longitudinally on said chuck, a plurality of manually releasable plungers resiliently mounted in said collar, clamping means pivoted externally on said chuck, linkage connecting said clamping means and plungers, and manually operable means for normally holding said collar in a predetermined position longitudinally of the chuck.
- 30 7. A cord assembling fixture comprising a manually rotatable plug holding chuck, a collar rotatable with and slidably longitudinally on said chuck, a plurality of manually releasable plungers resiliently mounted in said collar, clamping means pivoted externally on said chuck, linkage connecting said clamping means and plungers, and a latch for normally holding the collar in a position for rendering the plungers operative.
- 35 8. A cord assembling fixture comprising a manually rotatable plug holding chuck, a collar rotatable with and slidably longitudinally on said chuck, a plurality of plungers resiliently mounted in said collar, clamping means pivoted externally on said chuck, linkage connecting said clamping means and plungers, and means for normally holding said collar in a predetermined position longitudinally of the chuck, each of said clamping means being provided with a clamping

surface for engaging a conductor and with a pin for engaging a terminal on a conductor.

9. In an assembling apparatus, a spindle, a spring chuck on the end of the spindle for receiving a plug, individually releasable clamps surrounding said chuck for gripping conductor terminals, resilient means normally holding said clamps closed, a collar slidable on said chuck for supporting said resilient means, and latching means for normally holding said collar in position to render the resilient means operative, each of said clamping means being provided with a clamping surface for engaging a conductor and with a pin for engaging a terminal on a conductor.

10. A cord assembling fixture comprising a manually rotatable plug holding chuck, clamps mounted on said chuck, a manually operable plunger connected to each clamp, means for urging said plungers to actuate the clamps, and releasable means for normally holding said urging means in operative position, each of said clamping means being provided with a clamping surface for engaging a conductor and with a pin for engaging a terminal on a conductor.
